UNITED STATES PATENT OFFICE.

EDWIN J. BLOOD, OF CHICAGO, ILLINOIS.

HAME TUG AND TRACE ADJUSTER.

SPECIFICATION forming part of Letters Patent No. 276,555, dated May 1, 1883.

Application filed March 6, 1883. (No model.)

To all whom it may concern:

Be it known that I, EDWIN J. BLOOD, of Chicago, county of Cook, and State of Illinois, have invented certain new and useful Improvements in a Hame Tug and Trace Adjuster, of which the following is a full, clear, and exact description, that will enable others to make and use the same, reference being had to the accompanying drawings, and to letters of reference marked thereon, forming a part of this specification.

This invention relates to that class of trace-adjusting devices which dispense with the use of a buckle, making it unnecessary to perforate the trace or tug at stated intervals in order to lengthen or shorten the same, as may be required.

Figure 1 is a side elevation of the front end of a trace, showing the fastening devices connected therewith. Fig. 2 is a side elevation, broken away, of a metallic sheath, showing the outside. Fig. 3 is a longitudinal section, showing the relative position of the trace and inclosing-sheath. Fig. 4 is a transverse section of the same; Fig. 5, a section of the front end of the sheath, and the clevis or eye connected therewith, which engages with the staple in the hames; and Fig. 6 is a modification.

Referring to the drawings, A represents a metallic sheath of a rectangular form, the outer sides being provided with a number of openings, a, placed at regular intervals, as shown in Fig. 2 of the drawings. The inner side of this sheath is open, but is provided with the longitudinal flanges a¹ a², as shown in Fig. 4 of the drawings, which are adapted to overlap the edges of the trace, preventing the same from being forced laterally out of the sheath, and forms guides for the ends of the cross-bar b of the locking-catch E. This sheath may be finished so as to be of a highly ornamental character, or covered with leather, as taste may desire. The front end of the sheath is provided with the prolongation or lug a³, which is perforated for the passage of the bolt a⁴, securing the clevis B thereto. The lug a³ enlarges toward the end, the contour conforming to the inner curved lines of the jaws of the clevis, which form of construction strengthens these parts and prevents the strain from all being thrown on the bolt a⁴. This clevis is of the

form shown; and is adapted to engage with the staple in the hame and detachably secure these parts in relation thereto.

The front end of the trace or tug C is provided with the clip D, which is bent or curved around the end of the trace and riveted thereto, as shown in Figs. 1 and 3 of the drawings. There is sufficient space left between the end of the trace and the inner curved end of the clip D for the passage of the bar b, which secures the back end of the locking-catch E to these parts, and provides an axial bearing or joint for the same, the opposite end being provided with the hook end b', having a square bearing-surface, and adapted to engage with the square shoulder of the square aperture in the sheath A. The outer side of the clip D is recessed for the reception of the back end of the flat spring d, one end of which is riveted or otherwise rigidly secured thereto, while the opposite end passes through the opening in the catch E, as shown in Figs. 1 and 3 of the drawings, and exerts a pressure on the back side of the same, serving to automatically throw the hook end of the catch into engagement with the sheath A and retain the same in a locked position.

It will be observed that the apertures a in the sheath are of a square form, and are curbed, so as to give these parts the necessary strength. The form of the hook end b' is of such dimensions and shape as to correspond to the apertures, the square end b² projecting over the edge of the curb, as shown in Fig. 3 of the drawings. By this arrangement the trace or tug is easily and conveniently lengthened or shortened, as may be required, the operator simply pressing the hook inward with the finger of one hand, so as to disengage the same from a locking position, the other hand adjusting the trace, the hook automatically engaging with the next aperture to which it may be adjusted.

Fig. 6 shows the front end of the sheath constructed with an eye in the end, so as to permit of the same being connected with the hame by the usual hame-straps.

Having thus described my invention, what I claim, and desire to secure by Letters Patent, is—

1. The rectangular sheath A, having the elongation a³, and provided on the outer side with

a series of curved apertures, a , while the back side is provided with the inner projecting flanges, a' a^2 , substantially as described.

2. The combination, with a harness-trace, of the sheath A, provided with inner projecting flanges, a' a^2 , adapted to overlap the edges of the trace, substantially as described.

3. The combination, with the trace C, of the clip D, overlapping the end and riveted to both sides thereof, and the locking-catch E, provided with the bar b, inserted between the end of the trace and the inner curved end of the clip, providing an axial bearing or joint for the adjustment of these parts, substantially as and for the purpose set forth.

4. The combination, with the clip D, of the spring d, having one end rigidly secured thereto, and the locking-catch E, the loose end of said spring being adapted to press against the back

side of said catch for the purpose of retaining the same in a locked position relative to the sheath A, substantially as set forth.

5. In a trace-adjusting device, the combination of the following instrumentalities, consisting of the sheath A, the clevis B, the trace C, the clip D, the spring d, and the locking-catch E, provided with the hook end b', substantially as and for the purpose set forth.

6. The combination, with the sheath A, provided with prolongation a^3 , of the detachable clevis B, adapted to connect these parts with the staple or other fastening device in the hames, substantially as described.

EDWIN J. BLOOD.
